UNITED STATES PATENT OFFICE.

WALTER P. KRUCK, OF SIOUX CITY, IOWA.

SAFETY CIRCUIT FOR STARTING MOTORS.

Application filed March 13, 1924. Serial No. 698,926.

To all whom it may concern:

Be it known that I, WALTER P. KRUCK, a citizen of the United States, residing at Sioux City, in the county of Woodbury and 5 State of Iowa, have invented a new and useful Safety Circuit for Starting Motors, of which the following is a specification.

An object of my invention is to provide a circuit to be used in combination with the 10 starting and ignition circuits of an automobile which employs an induction coil for producing high tension current for the spark plugs.

More particularly it is my object to provide such a circuit wherein a switch is interposed between the source of current and the induction coil and the switch is operable by suitable mechanism so as to be 15 opened when the spark of the car is so advanced that the car will be likely to back fire.

Still another object is to provide such a circuit which will use current from the 20 source of electrical energy only when the starting switch is closed.

Still more specifically my invention contemplates the employment of a switch interposed between the source of current and the ignition coil, operable by a magnet. The 25 magnet in turn is energized by the same source of current acting through a circuit which includes the starting switch and a third switch, normally closed, but which is opened by the rotation of the distributor or timer of the car when such distributor or timer is adjusted to a position where the 30 spark is retarded properly for starting.

With these and other objects in view, my 35 invention consists in the construction, arrangement and combination of the various parts of my device, whereby the objects contemplated are attained, as hereinafter more fully set forth, pointed out in my claims, and 40 illustrated in the accompanying drawings, in which:

Fig. 1 is a combined elevation and diagrammatic view illustrating the timer casing 45 of a car, a portion of the dash, and the coil box mounted thereon, the safety switch

and magnet therefor being shown in its case- 50 ing, the latter being in section.

Fig. 2 is a diagram of my invention as applied to another make of car employing the make-and-break distributor system of ignition. 55

Fig. 3 is a detail view taken on the line 3-3 of Fig. 1.

I have used the reference character 10 to indicate generally the dash of an automobile, and the reference numeral, 11, to indicate the coil box mounted thereon. Projecting through the back of the coil box and through the dash, 10, are the binding posts, 12, 13 and 14. The binding post, 12, connects to the secondary of the coils and to the spark plugs of the engine. The binding post, 13, is connected to the timer, which will hereinafter be described, and connects the primary and secondary of the coils. The binding post, 14, connects to the other 60 side of the primary of each coil. 70

On the front of the engine, which is not shown, herewith, is the time gear casing, 15, on which is mounted the timer casing, 16, held in place by the spring arm, 17. The 75 timer casing, 16, is rotatably mounted and controlled by the rod, 18, which is pivoted in the lug, 19, on the timer casing. The wires, 20, connect the timer binding posts, 21, within the respective binding posts, 13, of 80 the coil box.

Within the timer casing is the ordinary rotating brush, not shown, which successively contacts with insulated terminal blocks connected with the binding posts, 21, in order to form an electrical connection between the conductors, 20, and the timer casing for 85 grounding the coils.

Before proceeding further, it may be mentioned that in the drawings the ordinary 90 circuit now used on the automobile is shown in light lines, and the circuit which forms my invention in heavy lines.

The battery, 22, is grounded at 23, to the frame of the car, and connected by a conductor, 24, to the ignition switch, 25, which in turn is normally connected by a wire, 26, to the terminal post, 14. The magneto, 27, is 95

in like manner connected through the switch, 25, to the terminal, 14, and either may be employed by shifting the switch, 25. It will be seen that current may pass from either the battery, 22, or the magneto, 27, to the primary of the induction coils, and thus through the coils to the conductors, 20, and thence back through the timer, 16, to the engine base. At the same time the induced current in the secondary of the coils will flow through the spark plugs to the posts, 12, thence through the secondary of the coils and back to the engine through the conductors, 20. The starting motor, 28, is grounded at 29 to the frame of the car and connected by a conductor, 30, to the starting switch, 31, which is in turn connected by the conductor, 32, to the battery, 22.

In installing my device the wire, 26, is removed from the binding post, 14. The safety switch is housed in a casing, 33, supported by the brackets, 34 and 35, which are mounted on the coil box supporting bolt, 36, and binding post, 14, respectively. The bracket, 35, serves as a conductor and has an in-turned ear, 37, on which is mounted the contact member, 38. The other contact member, 39, is mounted on a swinging armature, 40, pivoted to the bracket, 41, on the removable cover, 42, of the casing, 33. A spring, 43, urges the contact points together.

It will be noted that the contact, 38, is connected to the binding post, 14. The contact, 39, is connected by a suitable conductor, 44, fastened to the swinging armature, 40, to the binding post, 45, in the cover of the casing. The binding post, 45, in turn receives the wire, 26.

It will be noted that the safety switch has thus been interposed between the ignition switch, 25, and the primary of the coils. In order to operate the swinging armature, 40, a magnet, 46, is provided, which is connected by suitable conductors to the binding posts, 47 and 48, which are in turn connected by the wires, 49 and 50, to the engine casing and battery, respectively, in the manner hereinafter described.

In order to interpose the starting switch, 31, between the magnet, 46, and the battery, 22, the wire, 50, is connected to the starting switch on the same side as the motor, 28. In order to do this, the wire, 50, is simply connected to the terminal of the motor at the same point where the wire, 30, terminates. The wire, 49, is grounded through a switch which will now be described.

Mounted on the time gear housing is the bracket, 51, which has the downwardly-extending arms, 52 and 53, respectively, designed to receive the bolts, 54 and 55, respectively, in the front and side portions, respectively, of the time gear housing.

Mounted on the arm, 52, is a pivot pin, 56, on which is pivoted the switch lever, 57.

A coil spring, 58, tends to urge the upper end of the switch toward the stationary contact, 59, and to thus close the switch.

The contact, 59, is mounted on an insulated block, 60, which is in turn fixed to the bracket, 51. The contact, 59, is connected by the conductor, 49, to the binding post, 47. The lower end of the lever, 57, extends across the path of movement of the lug, 19, and is adapted to be engaged thereby when the spark lever is moved in the direction indicated by the arrow, 62, for retracting the switch member from the contact, 59, and thus opening the switch. When the spark is retarded to the proper position for starting so that the motor will not back fire, the lug, 19, engages the lever, 57, and opens the switch. As soon as the spark has been advanced beyond a safety point where the motor is likely to back fire, the lever, 57, will be disengaged and the switch allowed to close. After the switch is depressed it will be seen that a circuit will be completed which includes the battery, 22, the conductor, 32, the switch, 31, the conductor, 50, the magnet, 46, the conductor, 49, the switch lever, 57, and the frame of the car. As a result, the magnet will be energized and will draw the armature, 40, toward it so as to separate the contacts, 38 and 39, and thus open the ignition circuit so that no current may be supplied to the primary of the coils.

In order to bring to the driver's attention the fact that the ignition circuit has been disconnected, an alarm, 61, may be shunted across the magnet, 46, so that when the magnet is energized the alarm will be operated. Either a buzzer, a small light, or both, connected in parallel, may be used.

In Fig. 2 I have shown the same safety circuit applied to a slightly different form of ignition circuit. The ignition circuit here shown is employed on many types of cars and includes the induction coil, 62, which has its primary connected at 63 through the safety switch to the starting switch, 25, and on the other side to the insulated contact of the interruptor, 64. The interruptor is operated from the same shaft as, and forms a part of, the distributor, 65, which distributes the current from the secondary, 66, of the coil, 62, to the spark plugs, 67. The switch, 57, may be suitably operated by the distributor casing in a manner similar to that employed in the switch already described.

It will be seen from the foregoing description that my device will prevent the engine firing while the starting motor is turning and while the spark is advanced. My device is very simple in construction and easy to install. There are no parts which will wear out, and it is difficult for the parts to get out of adjustment.

The device draws current only when the

starting motor switch is depressed, so that if the car is running the spark may be advanced without the device operating.

5 The word "timer" as used in the claims refers to either the commercially known timer or distributor.

Some changes may be made in the construction and arrangement of the parts of my invention without departing from the 10 real spirit and purpose of my invention, and it is my intention to cover by my claims, any modified forms of structure or use of mechanical equivalents, which may be reasonably included within their scope.

15 I claim as my invention:

1. In combination with an electrical circuit having primary and secondary ignition circuits, induction coils included in each of said circuits, a source of current in the primary circuit, a timer in the secondary circuit, a starting motor, a starting switch and a starting circuit including said starting motor, said starting switch and the source of current; a safety switch interposed in the 20 primary circuit, said switch including a movable arm having an armature, a magnet adapted to attract said armature for opening the safety switch when energized and thus to prevent current passing through the 25 primary of the induction coil, a controlling circuit for the magnet, said controlling circuit including a switch operable by the adjustment of the distributor and including the starting switch, the parts being so arranged that when the distributor is adjusted 30 so as to advance the instant of connection of the respective spark plugs with the induction coil, the controlling switch will close when the starting switch is also closed.

40 2. In combination with an electrical circuit having a primary ignition circuit, a secondary ignition circuit, an induction coil included in both circuits, a timer in the secondary circuit, a source of current in the primary circuit, a starting motor connected with said source of current by a starting circuit and a switch in said starting circuit; a safety switch interposed between the source of current and the primary of the induction coil, a magnet for controlling the safety switch, a controlling circuit including the magnet, the starting switch and a controlling switch, the controlling switch being operable by the timer so that adjustment of the distributor for advancing the spark will allow the controlling switch to close, the parts being so arranged that when the starting switch is closed and the controlling switch is closed, the magnet will be energized for opening the safety switch.

45 3. In combination with an electrical circuit having primary and secondary ignition circuits, an induction coil included in each of said circuits, a source of current in the primary circuit, a timer in the secondary

circuit, a starting motor, a starting switch and a starting circuit including said starting motor, said starting switch and the source of current; a safety switch interposed in the primary circuit between the source of current and the induction coil, means operable by the depressing of the starting switch for opening said safety switch, and means operable by adjustment of the timer to prevent the operation of said last means when the 75 distributor is adjusted so as to retard the spark.

4. In combination with an electrical circuit having an ignition circuit including spark plugs and a timer, and a starting circuit including a starting switch and a source of current for said electrical circuit, means for preventing the passing of a high tension current through the spark plugs, said means being operable by the depressing of the starting switch, and means controlled by the adjusting of the timer to prevent said last means from operating when the timer is adjusted so as to retard the spark.

5. In combination with an electrical circuit including an ignition circuit having spark plugs, and a starting circuit, having a starting switch, means for preventing the passing of current to the spark plugs, including an electromagnet energized from the starting circuit when the starting switch is depressed.

6. In combination with an automotive vehicle having an engine housing, an ignition circuit including a timer having a portion mounted for oscillation relative to said housing, said portion having a protruding member, said ignition circuit including also a plurality of spark plugs, and a source of current, means for preventing the passing of current to the spark plugs when the spark is advanced, including a switch lever fulcrumed on the housing and having a portion extending into the path of oscillation of said protruding member.

7. In combination with an automotive vehicle having a dash, a coil box supporting bolt extending therethrough, and a binding post mounted thereon, and an ignition circuit including said binding post, a plurality of spark plugs and a source of current; means for preventing the passing of current to said spark plugs, including an electromagnet, and a mounting for said magnet including a casing, and brackets fixed to said casing and attachable to said bolt and binding post, one of said brackets serving as part of an electrical circuit including said magnet.

8. In combination with an automotive vehicle having an engine housing, a timer casing, cap screws connecting said timer casing with the engine housing, an ignition circuit including a timer having a projecting element, spark plugs and a source of cur-

4
rent, means for preventing the passing of current to said spark plugs, when the timer is adjusted so as to advance the spark, including a switch lever having a portion disposed in the path of movement of said projecting element, a bracket having a pair of legs attachable to said cap screws, said

switch lever being fulcrumed on said bracket, and a coacting switch element fixed to the bracket.

10
Signed at Sioux City, in the county of Woodbury and State of Iowa, this 16th day of February, 1924.

WALTER P. KRUCK.
